SOUND-EXCLUDING VENTILATING
WINDOWErnest Thomas Fisk, Sydney, New South Wales,
AustraliaApplication October 4, 1937, Serial No. 167,305
In Australia October 28, 1936

8 Claims. (Cl. 98—88)

This present invention relates to sound-excluding ventilating windows.

The object of the invention is to provide means, in ventilating windows of the kind in which two or more glazed panels fit three sides of the window aperture leaving ventilating spaces on the fourth side, for facilitating access to the glazed panels thereof for cleaning purposes, without affecting adversely the operation of the sound excluding and ventilating features of the window; a further object is to provide a simplified and less expensive construction than that involved in the prior arrangement.

A window embodying the present invention is illustrated in the accompanying drawings, in which Figure 1 is a vertical cross section; Figure 2 is a horizontal section.

Figure 3 is a vertical cross section of a modification of the arrangement according to Figure 1; and Figure 4 is a horizontal section of window showing the main panels divided vertically down the centre.

Referring to Figure 1, 10 is a short outer fixed glazed panel extending across the window opening, from the sill 12 upwards, but with a vacant space above it. A movable glazed panel 13 is hinged to the side of the window frame at 14 to swing inwards; when closed outward this panel 13 aligns with the fixed glazed panel 10. Above the top of the hinged panel 13 a ventilation opening 15 is provided under the frame head. A central fixed glazed panel 16 rearward of the opening 15 extends across the window opening from the frame head 17 downwards terminating slightly above the level of the top end of the hinged sash 13. A second movable glazed panel 18 is hinged to the frame side 19 and aligns when closed outward with the central fixed glazed panel 16, but terminates above the sill 12 about level with the top of the fixed sill panel 10; a ventilation well 20 is formed below it, between the sill panel 10 and a glazed panel 25 which extends up from the inner sill of the window frame, parallel with the panel 10. A glazed panel 24 also extends from the frame head downwards to about the level of the top edge of panel 13.

An inner glazed panel 21 extends across the top part of the window opening from the head downwards to a level slightly above the level of the top of the sash 18; this panel 21 is hinged at 22 to swing inwards and upwards. A corresponding lower glazed panel 23, in plane with the swing panel 21, extends across the lower part of the window opening, from the sill upwards to the same height as the panel 25, and close to it;

this panel 23 is hinged at 26 to swing inwards and downwards. The two glazed panels 24 and 25 are associated respectively with the hinged panels 21 and 23 and are slideable on guides so that they may be moved in a vertical direction to reduce or if desired to close the space between the panels 21 and 23.

The hinged panel 13, when swung in, as shown in dotted lines, clears the bottom ends of the fixed central top panels 16 and 21 and 24, and also clears the top ends of the bottom inner panels 23 and 25. The hinged panel 18, when swung inwards as shown in the dotted lines, clears the panels 21, 24, 23 and 25. The panels 13 and 18 may both be hinged at one side of the window frame as shown in Figure 2 or one at each side frame.

In the improved structure provided by this invention the outer and middle sashes are hinged to swing inwards to facilitate cleaning and to obtain a large window opening without disturbing any of the four inner glazed sashes, viz., 21—24 and 23—25. It also renders it practicable to dispense with the hinges 22 and 26 and to fix the sashes 21 and 23 permanently in the frame. In this case opening of the window for ventilation whilst retaining its effectiveness for sound reduction is effected by sliding the sashes 24 and 25.

Whilst it is preferable that a slideable panel 24 should be associated with the hinged panel 21 and that a slideable panel 25 should be associated with the hinged panel 23, these slideable panels 24 and 25 may be omitted from the assembly without destroying its integrity and without materially depreciating its utility.

Leakways for clearing storm water from the chamber 20 are provided at the foot of the panel 10.

Figure 3 is a modified form of the window; as before 30 is a short outer fixed glazed panel extending across the window opening, from the sill 32 upwards and a movable glazed main panel 33 is hinged to the side of the window frame at 34 to swing inwards; when closed outwards this panel 33 aligns with the fixed glazed panel 30. Above the top of the hinged panel 33 a ventilation opening 35 is provided under the frame head 37. An inner glazed main panel 38 is hinged to the window frame side at 39 rearward of the opening 35, extends across the window opening under the frame head 37 and terminates downwardly at approximately above the sill 32 at about the same level as the top of the fixed sill panel 30. A ventilation well 40 is thus formed below

said main panel 38 between the sill panel 30 and a glazed panel 45, which extends up from the inner sill of the window frame 32 parallel with and at approximately the same height as the panel 30. In this case the main panel 38 is in one piece.

By extending the top edge of the inner sill panel 45 above the level of the top of the fixed outer panel 30 and hinging said panel 45 to swing both inwards and outwards, the necessary clearance can be provided for enabling the main panels 33 and 38 to swing inwards, while when the main panels are in their normal position the window opening may be entirely closed by swinging the panel 45 in an outward direction until its top edge bears against the lower framing of the main panel 38.

When constructing windows of great width it is convenient for the main panels to be divided vertically into two or more portions. This is seen in Figure 4 which is a sectional plan view across a window similar to that shown in Figure 2. In the modification the panels 13 and 18 are framed up in two equal portions so that the adjacent vertical parts of the framing abut one another as in casement sashes while the outer vertical parts are hinged to the opposite reveals, whereby both double sashes 13 and 18 are adapted to swing inwardly.

From the foregoing description it will be seen that the arrangement of panels provides for minimizing sound transmission while permitting transmission of light from one side to the other side of the window.

It will further be understood that some or all of the unglazed surfaces within the aperture may be lined or treated with any known material specially adapted for sound wave dampening.

I claim:

1. The combination with a window frame, of a window fitment in the frame comprising inner and outer vertically disposed glazed structures which are separated laterally by an air space and overlap to a considerable extent, the outer frame structure engaging the frame at its two sides and at the sill but being spaced from the top of the frame, said outer structure being divided horizontally into upper and lower panels, the upper one of said panels being hingedly mounted whereby it may swing inwardly, the inner glazed structure engaging the window frame at its two sides and top of the latter, and having its lower end spaced from the sill, the inner structure comprising a hingedly mounted portion adapted to swing inwardly to permit the upper panel of the outer structure to swing inwardly.

2. The combination with a window frame, of a window fitment in the frame comprising inner and outer vertically disposed glazed structures which are separated laterally by an air space and overlap to a considerable extent, the outer frame structure engaging the frame at its two sides and at the sill but being spaced from the top of the frame, said outer structure being divided horizontally into upper and lower panels, the upper one of said panels being hingedly mounted whereby it may swing inwardly, the inner glazed structure engaging the window frame at its two sides and top of the latter, and having its lower end spaced from the sill, the inner structure comprising upper and lower panels hingedly mounted in the frame, the lower one of the last mentioned panels being adapted to swing inwardly to permit the upper panel of the outer structure to swing inwardly.

3. The combination with a window frame, of a window fitment in the frame comprising inner and outer vertically disposed glazed structures which are separated laterally by an air space and overlap to a considerable extent, the outer frame structure engaging the frame at its two sides and at the sill but being spaced from the top of the frame, said outer frame structure being divided horizontally into upper and lower panels, the upper one of said panels being hingedly mounted whereby it may swing inwardly, the inner glazed structure engaging the window frame at its two sides and top of the latter, and having its lower end spaced from the sill, the inner structure comprising a panel of substantially the same height as the inner structure, hingedly mounted in the frame and adapted to swing inwardly to permit the upper panel of the outer structure to swing inwardly.

4. A window fitment consisting of two main vertically disposed framed glazed structures which are separated laterally by an air space, comprising an outer framed structure fitting the window aperture at the two sides and the sill leaving an opening at the top side, said structure being divided horizontally into two panels, an inner framed structure fitting the window at the two sides and the top leaving an opening at the lower side, this framed structure being divided horizontally into two panels and having hinges on the lower panel, and a further framed structure separated laterally by an air space from the inner framed structure, this further structure being divided horizontally into four separate narrow panels of substantially equal height, one such panel being fixed to the sill and another at the top of the aperture and each closing the window aperture at the two sides, the other two panels having sliding means enabling them to slide respectively upwards and downwards close to the first two mentioned narrow panels, so that when the said inner sliding panels are opened they form a clear space through which the hinged panels of the main structures can pass.

5. The combination with a window frame, of a window fitment in the frame comprising inner and outer vertically disposed glazed structures which are separated laterally by an air space and overlap to a considerable extent, the outer frame structure engaging the frame at its two sides and at the sill but being spaced from the top of the frame, said outer structure being divided horizontally into upper and lower panels, the upper one of said panels being hingedly mounted whereby it may swing inwardly, the inner glazed structure engaging the window frame at its two sides and top of the latter, and having its lower end spaced from the sill, the inner structure having its lower edge arranged in substantially the same plane as the upper edge of the lower panel of said outer structure, the inner structure having a portion hingedly mounted in the window frame and adapted to swing horizontally inwardly to permit the upper panel of the outer structure to swing inwardly, and an additional panel separated laterally from the inner structure by an air space and extending from the sill of the frame upwardly to approximately the same height as the upper edge of the lower panel of the outer structure to allow the upper panel of the outer structure as well as the hinged portion of the inner structure to swing inwards through the space above said additional panel.

6. A combination as claimed in claim 5 in

which said additional panel is movably mounted in the frame whereby it may be opened or closed to adjust the degree of ventilation.

7. A combination as claimed in claim 1 in which the upper panel of the outer structure and the hinged portion of the inner structure are hinged to swing horizontally inwardly.

8. A combination as claimed in claim 1 in which the hinged panel of the outer structure and the hingedly mounted portion of the inner structure are each divided vertically into two sections, each section forming a vertically hinged sash adapted to swing in a horizontal plane. 5
